UNITED STATES PATENT OFFICE.

CHARLES A. GREEN, OF ST. LOUIS, MISSOURI, ASSIGNOR OF ONE-HALF TO JOHN E. SWANSON, OF BOSTON, MASSACHUSETTS.

WORK SUPPORTING AND GUIDING DEVICE.

1,385,538.

Specification of Letters Patent. Patented July 26, 1921.

Application filed November 15, 1919. Serial No. 338,357.

To all whom it may concern:

Be it known that I, CHARLES A. GREEN, a citizen of the United States, and resident of St. Louis, county of St. Louis City, State of Missouri, have invented an Improvement in Work Supporting and Guiding Devices, of which the following description, in connection with the accompanying drawing, is a specification, like characters on the drawing 10 representing like parts.

This invention relates to improvements in work supporting and guiding devices for moving the work in a predetermined path relatively to a fixed point whereby a desired line may be traced upon the work.

More specifically the invention relates to improvements in shoe making machinery, and comprises means whereby a predetermined mark, line of perforations, or line of 20 stitching may be applied to a part of a shoe, such as the line marking the usual tip of the vamp of a shoe in imitation of a cap.

In a construction of certain types of shoes an arcuate line of stitching is made across the tip of the vamp to simulate a toe cap. This is usually accomplished in a series of operations. When the vamp is cut by hand from a pattern the cutter usually stamps two points on opposite edges of the vamp 30 to indicate the end of the line of stitching, or of perforations. Another operator lays a form upon these points and scribes a mark connecting them. When dies are used for cutting vamps for such purposes the dies are provided with means for cutting notches at the proper points in the edges of the vamp. The stitcher then sews one or more rows of stitching along the line thus marked. This line of stitching is curved, being either 40 a section of the circle, an erratic curve or an irregular fanciful curve, and it requires a careful operator to follow the line with accuracy.

The present invention contemplates the provision of a work supporting device which may be moved by the hand, or otherwise, and which during its movement will be so guided as automatically to pass the work by a fixed point in such a manner that the fixed point 50 will pass over a predetermined line upon the work. When the device is used in combination with a sewing machine the work support is so guided that the operator is required merely to position the vamp, or other article being operated upon, properly upon

the work support and move the same forward, the work support then being guided in such a manner as to produce the desired line of stitching whether the same be an arcuate line, or an erratic curve, or a fanciful line. 60

It will be understood that while the device illustrated herein is particularly adapted for use in connection with the sewing machine it may be employed in combination with any other type of machine which is adapted to 65 scribe a line or to produce a series of perforations or to apply any desirable design for which the device is adapted.

A preferred embodiment of the invention is illustrated herein as applied to the table 70 of a sewing machine.

In the drawings:

Figure 1 is a plan view of a vamp illustrating in dotted lines a line of stitching simulating the edge of the toe cap of the 75 shoe.

Fig. 2 is a plan view of a preferred form of work support and guide embodying my invention.

Fig. 3 is a detail plan view of a modified 80 form of pivotal connection for a work support of the type illustrated in Fig. 2, the greater part of the work support being broken away.

The work support and guide illustrated 85 in the accompanying drawings is shown as applied to the table 1 of a sewing machine of any usual type, provided with a vertical reciprocating needle or needles 2 which are diagrammatically illustrated in their position relatively to the table and work support. 90

The sewing machine may have the usual presser foot and feeding mechanism and may operate in the usual manner. It has 95 therefore not been deemed necessary to illustrate the sewing machine in detail.

The preferred form of work support and guide which is illustrated herein comprises 100 a work supporting member or plate 3 preferably substantially in the form of a segment of a circle, having an arcuate slot 4 to provide a path for the needle of the sewing machine as the work supporting member is moved forward and backward.

The work supporting member or plate 3 may be mounted upon a fixed pivot 5, in which case it will have a true circular movement and will be adapted to carry the work in such a manner as to produce a line of 110

stitching, which is a section of a circle, upon the work carried by the work support.

A shoe vamp 6 such as is shown in Fig. 1 is illustrated in Fig. 2 in dotted lines as in 5 the proper position upon the work support. The vamp 6 is provided with notches 7 and 8 upon its opposite edges which serve to indicate the proper position with relation to the work support, and in order to position 10 the same properly when a true arcuate line of stitching is required an indicating plate 9 is secured to the work table 1 in such a manner that its arcuate edge 10 defines the line of stitching which will be formed 15 in the vamp as the work supporting member is oscillated. In order to position the vamp properly therefore, the notches 7 and 8 are placed directly over the arcuate edge 10 of the guide 9.

20 In many instances it is desirable that the line of stitching placed upon the vamp to indicate the margin of toe cap shall be an irregular curve and to accomplish this purpose means are provided which will enable 25 the work support to have a motion which is the resultant of a bodily radial movement, as well as the lateral movement which is imparted to it to carry the work past the stitching point. This is accomplished and 30 embodied in the invention disclosed in Fig. 2 by providing a slot 11 in the plate 3 to receive the pivot 5 to permit the radial bodily movement of the work supporting member. The work supporting member is 35 provided with a pattern slot 12 of the desired curvature or form, and the edge 13 of the pattern slot is normally held in contact with a guide, which desirably is in the form of a roller 14 mounted upon a 40 suitable stud 15 extending upwardly from the table 1. The edge 13 of the pattern slot is held in contact with the roller by resilient means such as a helical spring 16 which is mounted upon a stud 17 projecting from the 45 plate 3 and abuts at its opposite end against a block 18 which is fixedly secured to the table 1.

The plate 3 desirably may be provided 50 with an extending finger piece 19 by which it may be grasped to enable the plate to be oscillated readily about its pivotal support. It also desirably is provided with an upwardly extending projection or flange 20 which is adapted to engage the presser foot 55 of the sewing machine to limit the oscillating movement of the work support so that the needles of the sewing machine will not engage the metal of the work support.

In order to provide for the proper placing 60 of vamps which are not provided with notches or other indications for the ends of the line of stitching, and also to provide for different sizes of vamps, an adjustable guide desirably is secured to the work supporting plate. A preferred construction

which is disclosed herein comprises a guiding bar 21 which is slidably secured in ways formed in bosses 22 and 23 extending upwardly from the central portion of the plate 3, and the slide 21 is secured in adjusted position by a screw 24 seated in the slide 21 and adapted to engage the plate 3 and by such an engagement to clamp the slide against the ways. In use the slide 21 is so positioned that when it engages the central portion of the inner edge of the toe portion of the vamp, and the toe of the vamp placed in the same radius relatively to the pivotal stud 5, the vamp will be in proper stitching position.

80 Other means for pivotally mounting the work supporting plate may be employed, such as the preferred form illustrated in Fig. 3, in which the plate 3 is pivotally secured to a bar 25 which is slidably mounted 85 in a guide-way formed in the rectangular upper end 26 of a post 27 which is secured to the table 1. The slide 25 is provided at its opposite end with a helical spring 28 which abuts against a bracket 29 secured to the table 1. The spring 28, like the spring 16 in the construction shown in Fig. 2 serves normally to force the plate 3 outwardly, (to the right) so that the edge 13 of the pattern slot engages the guiding roller 14. A 95 set screw 30 mounted in the side of the rectangular upper end of the pivot 26 may be provided to engage and clamp the slide 25 against longitudinal movement, thereby securing the pivotal support of the plate 3 100 against movement, and enabling the work support to be swung in the true arc of a circle about its pivotal connection 31 with the end of the slide 25.

105 It will be understood that the embodiment of the invention disclosed herein is illustrative and not restrictive, and that various modifications in construction, size and arrangement of parts may be made within the spirit and scope of the following claims.

110 Having thus described my invention what I claim as new and desire to secure by Letters Patent is:

1. A work supporting and guiding device 115 for sewing machines comprising a manually movable pivotally mounted work supporting member having an arcuate slot therein to provide a path for the needle, and an arcuate guide located beneath said slot for indicating the position for the work upon said 120 work supporting member to cause the needle to produce a predetermined line of stitching in the work as the work supporting member is moved about said pivot.

2. A work supporting and guiding device 125 for sewing machines, comprising a plate having an arcuate slot therein to provide a path for the needle of the sewing machine, a pattern slot, a stationary guiding member in said slot, a pivot for said plate, and means 130

yieldably connecting said plate to said pivot acting to force the wall of said pattern slot against said stationary guide.

3. A work supporting and guiding device 5 for sewing machines, comprising a plate having an arcuate slot therein to provide a path for the needle of the sewing machine, a pattern slot, a stationary guiding member in said slot, a pivot for said plate, and 10 means yieldably connecting said plate to said pivot acting to force the wall of said pattern slot against said stationary guide, and a radially adjustable guide secured to said plate for positioning the work properly 15 thereupon.

4. A work supporting and guiding device for sewing machines, comprising a plate having an arcuate slot therein to provide a path for the needle of the sewing machine, 20 and a pattern slot having a wall correspond-

ing to the line of stitching to be made, a stationary guiding member in said pattern slot engaging said wall, a pivot for said plate, and means yieldably connecting said plate to said pivot, acting to force the wall 25 of said pattern slot against said stationary guide.

5. A work supporting and guiding device for sewing machines comprising a plate having a slot therein to provide a path for 30 the needle of the sewing machine, a pattern slot, a stationary guiding member in said slot, a pivot for said plate and means yieldingly acting upon said plate to force the wall of said pattern slot against said sta- 35 tionary guiding member.

In testimony whereof I have signed my name to this specification.

CHARLES A. GREEN.
